FOLDING CAP STAYER

Irving Libshutz and Harry Libshutz,
Baltimore, Md.

Application May 23, 1948, Serial No. 29,676

2 Claims. (Cl. 2—195)

1

This invention refers to clothing and more particularly to caps of the uniform type. It has among its objects to provide a new and improved uniform cap with a folding stayer that will avoid one or more of the disadvantages and limitations of the prior art, and is an improvement over that shown in Serial Number 731,358, filed February 27, 1947, now Patent No. 2,450,148, dated September 22, 1948.

Another object of this invention is to provide a new and improved uniform cap stayer frame that can be collapsed for packing, storing or shipping purposes, readily and neatly and also arranged so as to be returnable to its full open or working form, in a prompt, effective and substantial manner.

A further object of the invention is to provide a new and improved uniform cap that will, through the use of its foldable stayer frame, included in the invention, afford strength to the cap, stretch the material resiliently to a suitable and smooth degree and render it comfortable to wear on the head of the user.

Still another object of this invention is to have the stayer frame conformable to the internal contour of its cap, with which it is used, and including a folding mechanism that will snap quickly into place, whether to open or collapsed positions, as the occasion may require, and lock substantially therein. Also to include in its design an attachment element that will enable it to be secured to the material of the cap without the use of thread or sewing material, as frequently required in other caps.

A further object of the present invention is to provide a new and improved folding stayer for holding up the front of a uniform cap, and supporting a cap grommet thereon, and including means for frictionally holding the stayer open.

A further object of the present invention is to provide a cap stayer of hinged form, that can be attached to a cap frame and changed from an operating to a folded position without the use of tools or the like, when causing the uniform cap to be reduced in height at one portion by merely pressing on the stayer to cause it to bend inwardly and reduce the cap height for packing purposes and be ready for use by pressing upwardly on the bent portion until it snaps into the holding means ready for use.

The stayers used with uniform caps are rigid frames that stiffen the open uniform cap so it will present the military aspect intended for it. Such caps indicate by their solid and impressive appearance the resulting structure derived from

the need of helmets in previous times, to save their users from the onslaughts of weapons of war. The caps however while made of light and fabric materials which are flexible and soft, are also made to retain strength and solidity. To do this, some kind of light frame has been interposed in recent times, within the cap, sufficient to stretch the cap and enable it to retain its shape, even against relatively rough usage. In a particular form of stayer, the attachment is made by sewing, and there are several with disjointed parts. These parts require assembling and manipulation. This manipulation is involved during the collapsing and opening up of the cap. This takes time, and a certain amount of skill and care. The cost of such frames is relatively high and requires the use of metal or plastic or other rigid material that is thick, or strong and expensive. Adjustments and tightening arrangements employ the use of bolts and nuts, as well as other incidental parts, loose or partially separated or extended from the frame structure itself.

In order to illustrate the invention and make its principles clear, reference is made to the appended drawings, which together with the description following, indicate a particular form of the invention, by way of example, while the scope of the invention is emphasized in the claims.

Referring to the drawings:

Figure 1 is a side elevation of a uniform cap with portions of the front broken away and in section to show the stayer frame and its manner of assembly; the cap being in open position;

Figure 2 is a similar view with the cap collapsed and the stayer folded;

Figure 3 is an enlarged detail of the stayer frame; as seen from the front;

Figure 4 is a sectional view taken on line 4—4 of Figure 3;

Figure 5 is a sectional detail of the hinge lock used in this embodiment;

Figure 6 is a detail in section of the stayer frame similar to that shown in Figure 4, but in collapsed position; and

Figure 7 is a detail in perspective of the hinge lock mechanism with portions broken away to clarify the details of its construction.

Similar reference characters refer to similar parts throughout the drawings.

50 In the particular form of the invention shown, the drawings illustrate a uniform cap of conventional structure made of fabric sewed into a flat circular top 10, a flexible collapsible cap circular wall 11 and a wall band 12 of cylindrical form fitted to encompass the head of the user. A

grommet 9 is provided between the top 10 and the wall 11 to help maintain the cap in extended position. A peak or visor 13 of stiff semi-rigid material serves as an eye-shade at the front of the cap. The top 10 is held up at the front in an angular plane, as shown in Figure 1, when open, and rests closely on the wall band 12 when in collapsed position. A strap 14 ornamented by buttons 15 surrounds the front half of the wall band, is used as a chin strap and for aesthetic reasons. The wall band 12 consists of several layers of fabric, as in the conventional cap. In order to give the necessary stiffness to the cap when in open position, and yet not interfere with the movement required to collapse it, a stayer frame 16 of rigid material, preferably thin and flat, is fastened to the wall band 12 by pointed and tapered fasteners 17 stamped and bent out of its material. The fasteners 17 are forced into the material of the wall 12 and then bent flat between the layers so as to be secure and at the same time not conspicuous. Enough spaced fasteners are used to hold the lower plate 18 of the stayer frame in a rigid manner to the band 12. The plate 18 is slightly rounded in width to conform with the arc of the wall band 12 and the corners are removed to reduce the tendency for this plate to cut into or injure the cap material. The upper portion of this plate 18 is slotted out at 19 and formed with small adjacent depressed humps 20 and 22 serving as bearing portions to hold a hinge shaft 21 in place. Above the humps 20 and 22 but to the side thereof, are right-angled lugs 24 close to inwardly projected tips 25. A specially formed upper plate 26 of similar material to that of the lower plate 18, is spread out in greater area than that of the latter and reinforced with corrugations 28 to increase its stiffness and with material removed to form large openings 27 to lighten it while inducing sufficient lateral resiliency to allow it to conform with the contour of the cap against the wall 11, without detracting from its upstanding stiffness. The plate 26 is hinged to the shaft 21 by having an extended bottom hinge piece 28 of proper width and size to fit closely in between the journals when rolled around the shaft 21. The piece 28 of the plate is then formed into an S-like shape with portions 29 thereof serving to resiliently press through the tips 25 and rest against the lugs 24 as they are pushed through between the tips. The tips 25 act as stops to this piece 28 when the stayer frame is in open position, and hold the upper plate 26 rigidly in place, between the tips 25 and the lugs 24. The plate 26 is offset by the hinge piece 28 so as to move over and rest on the wall band 12 and press against the front of the cap wall 11, when open. The upper side of plate 26 is reduced in width and extended, with a portion 30 bent approximately at right angles and rounded at the extremity 31 to form a prop for the front top of the cap. It is fitted into the corner formed between the wall 11 and the top 10 of the cap to function as a substantial support without any tendency to injure the material or make the cap distorted to the outside view. The upper plate 26 is not fastened in any way to the cap material, and is therefore free to bend when hinged, without inducing any stresses thereon. The plate 26 is snapped into place at the journals and held at the tips 25, in open position, and when collapsed, snaps past the tips in a resilient manner to stay in that position. The stayer frame 16 is then in the folded position shown in Figure 2 neatly ex-

tended out of the way and having no parts liable to cause injury to the cap or the person manipulating it. The grommet 9 is flexible and consists of a band of whalebone, metal or plastic having an adjustable fastening (not shown) to enable it to be adjusted to the inside diameter of the cap, is used in the cap, and is termed a grommet. This grommet is inserted in its rounded form by suitable bending and manipulation. When in place, it is brought against the stayer frame when in open position to facilitate the placing of the latter as well as strengthening the top of the cap.

While but one general form of the invention is shown in the drawings and described in the specifications, it is not desired to limit this application for patent to this particular form or in any other way otherwise than limited by the scope of the claims, as it is appreciated that other forms of construction could be made that would use the same principles and come within the scope of the appended claims.

Having thus described the invention, what is claimed is:

1. The combination with a uniform cap having a flexible cap top, a grommet and a flexible wall band, of a stayer frame mounted internally of the cap top and at the front portion thereof, said stayer consisting of a lower plate and an upper plate having means for securing said lower plate to the wall band and hook means for engaging said upper plate to the grommet, hinge means between said plates, whereby said upper plate is selectively in erect position to maintain the front portion of the cap top in raised position and swingable inwardly of the cap top to a position at right angles to the lower plate to allow the front portion of the cap top to assume a collapsed position, said hinge means comprising cooperating bearing portions formed in the lower plate, a shaft having its ends received in said bearing portions, a hinge piece depending from the bottom of the upper plate, said shaft extending through said hinge piece, and resilient means on the upper portion of the lower plate adjacent said bearing portions to maintain the upper plate in erect position.

2. A stayer of the class described comprising a lower plate having spaced depressed humps at its upper end, a shaft having its ends positioned in said humps, said lower plate also having a pair of spaced-apart aligned lugs above said humps extending towards each other in the plane of the said plate and a pair of resilient tips adjacent to and below said lugs and extending at right angles to the plane of the said plate, an upper plate having a lower depending hinge piece bent around said shaft between said lugs, said hinge piece having portions to resiliently press against said tips and rest on said lugs when the upper plate is swung about said shaft.
